UNITED STATES PATENT OFFICE.

JAMES POLLOCK, OF NEW YORK, N. Y.

MINING-TOOL.

981,306.

Specification of Letters Patent. Patented Jan. 10, 1911.

Application filed October 4, 1909. Serial No. 520,862.

To all whom it may concern:

Be it known that I, JAMES POLLOCK, a citizen of the United States, residing in the borough of Brooklyn of the city of New York, in the State of New York, have invented certain new and useful Improvements in Mining-Tools, of which the following is a specification, reference being had to the accompanying drawings, forming a part hereof.

The invention has for its object to provide an improved and efficient drill or tool for use in the mining of coal for the purpose of forming at the inner end of the hole drilled to receive the charge of explosive a laterally enlarged chamber in order that the force of the explosion may be so directed as to be more effective in breaking down the coal, especially in the working of comparatively thin seams.

The invention will be more fully explained hereinafter with reference to the accompanying drawings in which—

Figure 1 is a view, partly in longitudinal section and partly in elevation, of the improved tool. Fig. 2 is a detail view in section, on the plane indicated by the line 2—2 of Fig. 1, but on a larger scale. Fig. 3 is a view showing the tool in working position.

In the mining of coal in comparatively thin seams, there is drilled into the coal body *a* from the face *b* a generally cylindrical hole *c* of suitable depth and diameter. Then the inner or farther end of this hole is spread or expanded or mushroomed by the improved tool, as indicated at *d*, in Fig. 3, so as to provide a large area of surface against which the force of the explosion of the powder or other explosive used may be exerted. The effect of explosion of the powder when spread out in the chamber *d* is to blow out the coal from the breast on lines which diverge from the chamber *d* toward the face of the working. Each charge, the force of which is mainly directed toward the face of the working, therefore breaks down more coal than would a similar charge placed at the inner end of a cylindrical hole, and moreover has less tendency to pulverize the coal.

The improved tool for the inner end of the hole comprises a body *h* adapted to fit freely within the cylindrical hole which is first drilled into the coal body and to enter to or nearly to the bottom of the same, and

a cutter *i* which can be extended laterally as the tool is rotated, suitable means being provided for supporting and rotating the tool. As shown, the body *h* is composed of two half cylinders *h'* and *h''*, so that they may be properly chambered internally, as at *h³*, to support firmly the cutting tool. The two parts may be held firmly together, as by a ring *k*, threaded upon a projecting hub *h⁴* at one end, and by a tube *l* which is threaded upon a similar projecting hub *h⁵* at the other end and forms the shank of the tool. Within the chamber *h³* of the body *h* is mounted a plunger *m* which is adapted to be moved longitudinally within the body, as by a rod *n* which is threaded, as at *n'*, in a cap *l'* secured to the outer end of the tube *l*, and is provided with a hand wheel *n²*.

The shank or bar *z'* upon which the cutter *i* is mounted is curved in the arc of a circle and is connected to the plunger *m*, as by a pin and slot connection *i²*, so that by the movement of the plunger in the chamber *h³* the cutter may be withdrawn within the body *h*, as shown in full lines in Fig. 1, or extended laterally, as indicated by dotted lines in the same figure, the cutter and its shank projecting from the body *h* through an opening *h⁶* provided therefor while the shank has rigid bearings against the wall of the chamber *h³* and on the walls of the opening *h⁶*. The chamber *h³* within the body *h* is of such dimensions as to permit the curved shank or bar to move in the arc of a circle within the body. The tool is rotated as the cutter is gradually extended and for this purpose the tube *l*, to which the body *h* is secured, may be provided with a gear *l²* driven by any suitable means, as by a motor *l³*, as indicated in Fig. 3. For clearing out the hole made by the cutter as it is formed air under pressure from the usual compressed air supply is directed into the hole. As shown in Figs. 1 and 3 an air hose *o* may be connected to a jacket *o'* swiveled on the tube *l* and having an annular chamber *o²* from which air may be admitted to the interior of the tube *l* through ports *o³*. From the tube *l* the air passes through channels *o⁴* in the end of the body *h*, into the chamber *h³* within the body, from which it escapes through a port *o⁵* which is properly placed to direct the air into the hole as it is formed by the cutter in the coal body. The cutter body *h* is spirally grooved externally, as at *p*, and the tube

l is provided with a spiral web *p'*, to carry the dirt removed from the hole outward to the face of the working.

In the use of the tool above described, it will be understood that when the cylindrical hole *c* has been formed in the usual manner, the tool *h* is introduced and the cutter *i* is gradually extended laterally as the tool is rotated, until the hole *d* has been expanded or mushroomed to the desired extent. The cutter *i* is then drawn back within the body of the tool and the tool itself is withdrawn from the hole so that the chamber *d* may be filled with the explosive.

15 I claim as my invention:

1. A tool for mining, comprising a body adapted to be introduced into a previously formed hole and to be rotated therein, said body being formed in two longitudinal parts chambered internally, said parts being extended to form hubs one at each end of the body, a ring engaging the hub at the forward end of the body, a tube threaded upon the hub at the other end of the body and forming the shank of the tool, a bar curved in the arc of a circle and carrying a cutter, said bar being mounted and guided in said body for movement in the arc of a circle to extend the cut-

ter laterally from the body, a plunger adapted for longitudinal movement in the chamber of the body and operatively connected to said bar, and means to move said plunger.

2. A tool for mining, comprising a body adapted to be introduced into a previously formed hole and to be rotated therein, said body being formed in two longitudinal parts chambered internally, a ring securing said parts together at one end, a tube smaller in diameter than the body and securing said parts together at the other end and forming the shank of the tool, a bar curved in the arc of a circle and supported and guided by said body for movement in the arc of a circle and carrying a cutter and a rod extended through said tube and operatively connected with said bar to extend the same, said body being formed externally with a spiral groove and said tube being provided externally with a spiral web.

This specification signed and witnessed this 30th day of September, A. D. 1909.

JAMES POLLOCK.
